UNITED STATES PATENT OFFICE

2,026,751

WINDOW

George A. Robbins, Hilliard Township,
Knox County, Ohio

Application October 18, 1934, Serial No. 748,772

5 Claims. (Cl. 189—64)

This invention relates to windows of the species shown in the Letters Patent of the United States issued to me August 14, 1934, No. 1,970,195, and an object of the invention is to provide simplified means for weatherproofing the window. Other objects of the invention will appear herein.

The invention is embodied in the example herein shown and described, the features of novelty being finally claimed.

10 In the accompanying drawing—

Figure 1 is an interior elevation of a fraction of a tile wall partially broken out and showing the window according to the invention installed therein.

15 Fig. 2 is a horizontal section looking down on the line II—II, Fig. 1.

Fig. 3 is an isometric perspective of the weather strip.

20 Fig. 4 is a larger detail view showing the latch engaging the glass pane in full lines and its unlatched position in broken lines.

Fig. 5 is a front view of the latch in connection with a fraction of the glass.

25 As in my former patent referred to the two glass panes 12, 12, rest and slide horizontally on metallic tracks in the window casing, end boxes, such as shown at 14, being provided into which the panes can be slid upon opening the window.

30 In the present instance a vertical angular strip 19, similar to the corresponding strip in my said former patent, is secured to each side of the window casing, and within each of said angular strips is inserted a weather strip of trough-like construction, such as shown in Figs. 2 and 3, the edge of one leg 16 of said trough-like strip pressing against the outer face of the glass while the other leg 16^a is bent inward as shown at 16^b to engage a corresponding bend in the angular strip 19. When the weather strip is inserted, as shown, it is prevented from accidental removal, as when the glass is slid, by reason of the engagement of the angular parts referred to. The weather strip can be inserted by springing the legs thereof toward each other.

35 The projecting edge of the angular strip 19 is utilized as a stop for supporting a fly screen.

To thwart would-be intruders the inner part of the window casing is shown as provided with a latch member 20 pivoted at 21 to a pair of legs 22 on a base 23, said base also provided with a leg 24 connecting which and said pivoted latch member is a coiled spring 25 adapted to draw the latch member toward the glass pane. Said glass pane is also provided with a notch 26 into which the free end of the latch member is drawn when the glass pane is in window closing position. If ventilation is desired at night a second notch 26^a

can be made in the pane in such a position as to permit a small opening and prevent ready external manipulation of the pane. The latching member can be swung to broken line position, as in Fig. 4, when the window is not to be locked in which case the coil spring of the latch holds the latch in disengaged position.

The latch member and its support can be economically formed out of sheet metal as shown.

The forms of the parts can be changed without departing from the gist of the invention as claimed.

What I claim is:

1. Means for weatherstripping a horizontally sliding window pane including a hollow vertical member secured on the building in which the window slides and a trough-like sheet metal member having one leg to engage said hollow vertical member, with its other leg engaging said pane.

2. Means for weatherstripping a horizontally sliding window pane including a hollow vertical member secured on the building in which the window slides and a trough-like sheet metal member constructed to be sprung into engagement with said hollow vertical member with one of its legs engaging said hollow vertical member, and its other leg engaging said pane.

3. Means for weather-stripping a sliding window pane including a longitudinal hollow member secured on the building in which the window slides, one leg of said hollow member being longitudinally bent, and a trough-like sheet metal member having one of its legs bent to engage the first mentioned hollow member while its other leg rests on the pane.

4. Means for weather-stripping a sliding window pane including a longitudinal hollow member secured on the building in which the window slides, one leg of said hollow member being longitudinally bent, and a trough-like sheet metal longitudinal member having one of its legs bent to engage the first mentioned hollow member while its other leg rests on the pane, said trough-like member adapted to be sprung into said engagement.

5. Means for weather-stripping a sliding window pane including a longitudinal hollow member secured on the building in which the window slides, one leg of said hollow member being longitudinally bent, and a trough-like sheet metal member having one of its legs bent to engage the first mentioned hollow member while its other leg rests on the pane, one of said engaging legs being of width to project at its edge beyond the other.

GEORGE A. ROBBINS.
